UNITED STATES PATENT OFFICE.

JAMES G. BROWN, OF ELKHART, INDIANA.

TRACK-SUPPORT.

1,041,423.

Specification of Letters Patent. Patented Oct. 15, 1912.

Application filed February 7, 1912. Serial No. 675,998.

To all whom it may concern:

Be it known that I, JAMES G. BROWN, a citizen of the United States, residing at Elkhart, in the county of Elkhart and State of Indiana, have invented certain new and useful Improvements in Track-Supports; and I do hereby declare the following to be a full, clear, and exact description of the invention, such as will enable others skilled in the art to which it appertains to make and use the same.

My invention relates to new and useful improvements in track supports and more particularly to a combined cross tie plate and rail brace.

The object of my invention is to provide a combined cross tie plate and rail brace having means for preventing relative movement of the rail and brace, and, a further object of my invention is to so construct the cross tie plate that portions thereof may be bent into engagement with the flange of the rail to hold the same in place.

Other objects and advantages of my invention will be hereinafter made clearly apparent in the specification and pointed out in the claim.

In the accompanying drawings I have shown the preferred form which my invention may take.

In said drawings, Figure 1 is a horizontal sectional view showing a cross tie having my improved form of combined tie plate and rail brace secured in position thereon. Fig. 2 is a sectional view as seen on line 2-2, Fig. 1, and, Fig. 3 is a vertical sectional view as seen on line 3-3, Fig. 1.

Referring to the drawings in which similar reference numerals designate corresponding parts throughout the several views, 40 4 is a tie of the usual or any preferred construction, upon the upper surface of which is adapted to be positioned my improved form of tie plate 5. Said plate 5 extends approximately from end to end of the tie and has near its opposite ends, upwardly and inwardly extending braces 6.

The braces 6 are cut away, as shown at 7, so that one side of the lower flange of a 50 rail 8 will be received therein when a rail

is placed adjacent said brace sections. The inner vertical surfaces of the braces are vertically serrated, as shown at 9. The upper surface of the brace section 6 is so formed as to fit snugly against the under surface 55 of one side of the head of a rail when the same is positioned adjacent said brace. Tongues 10 are struck from the plate 5 so as to extend vertically therefrom, as shown by dotted lines in Fig. 1.

When it is desired to secure a rail in place, the same is positioned against one of the brace sections 6 and the inner side of the rail is struck so as to cause the serrations 9 to bite into the side of the rail. 65 Tongues 10 are then bent outwardly against the side flange of the rail so as to hold the same securely in place. In order to hold the plate 5 in position upon the tie and to more securely hold the rail in place, I 70 provide the plate 5 with openings therethrough at points adjacent the position occupied by the lower flange of the rail and spikes 11 are driven therethrough into the tie, the heads of said spikes engaging the 75 upper surface of the rail flange.

By providing a tie-plate 5 having rail braces at its opposite ends, it will be seen that spreading of the rails will be prevented. It will also be seen that by providing 80 the rail engaging surfaces of the brace with serrations, relative movement of the rail and brace will be prevented.

What I claim as new is:

The combination with a tie; of a plate 85 adapted to be secured upon the upper surface thereof, inwardly extending rail braces formed at the opposite ends of said plate, vertically extending serrations formed in the inner surface of said rail braces, and 90 tongues formed from the adjacent portions of said plate adapted to be bent toward said rail braces to secure a rail therebetween.

In testimony whereof I have signed my name to this specification in the presence 95 of two subscribing witnesses.

JAMES G. BROWN.
